UNITED STATES PATENT OFFICE.

WILLIAM L. BROWN, OF LITTLE ROCK, ARKANSAS.

RAILWAY WATER-TANK.

No. 815,142.

Specification of Letters Patent. Patented March 13, 1906.

Application filed August 14, 1905. Serial No. 274,093.

To all whom it may concern:

Be it known that I, WILLIAM L. BROWN, a citizen of the United States, residing at Little Rock, in the county of Pulaski and State of Arkansas, have invented certain new and useful Improvements in Railway Water-Tanks, of which the following is a specification.

The invention to be hereinafter described relates to railway water-tanks, and more particularly to the means whereby such tanks may be maintained with a proper supply of water without the personal services of an attendant.

The objects of the present invention are to provide automatic means for maintaining at all times a sufficient quantity of water in a railway-tank and to control the supply by an automatic regulation of the pumping instrumentalities.

With the above general objects in view the invention consists of the parts and combinations to be hereinafter described, and definitely pointed out in the claims.

The drawing represents in side elevation and part section one embodiment of the invention, in which—

A is a water-tank of any usual or approved character properly supported—as, for instance, on the uprights A' A'. Disposed within the tank A is a bracket a, to which is pivotally connected an arm a', carrying a float a², whereby as the level of the water in the tank varies said float will rise and fall, turning the arm a' about its pivotal connection with the bracket a. Mounted upon the top of the tank are the uprights b, carrying a shaft b', upon which is loosely mounted an arm b², one end of which is connected to the float-arm a' by a link b³, the other end of said arm carrying a pivotally-mounted trip-catch, comprising the depending hook portion b⁴ and the trip-arm b⁵. A spring b⁶ normally acts upon the trip-catch, as shown, to carry the hook portion b⁴ to the left in the drawing. In the bottom of the tank is the valve c, fitted to an opening c' and having an upwardly-extended valve-stem c², which at its upper end is provided with a hook c³, adapted to be engaged by the hooked end of the arm b⁴ when the latter is raised, as will be obvious.

From the construction thus far described it will appear that as the level of the water in the tank A falls the float will gradually as-

sume the position indicated in dotted lines, 55 thereby turning the arm b² on the shaft b' and raising the trip-catch so that the hook-arm b⁴ will engage the hook on the valve-stem and raise the valve c from its seat.

Connected to the valve-opening c' of the 60 tank by suitable pipe c⁴ is a water-motor W of any usual construction, so that the column of water issuing from the tank when the valve c is raised will flow to said motor and in passing through the same in well-known manner will 65 operate the water-wheel and issue from the motor through the pipe c⁵.

Connected to the water-motor is the starting-shaft D, supported in bearings d d and provided with the worm d'. Splined to the 70 starting-shaft D, near one end thereof, is the sleeve d², carrying the beveled friction-gear d³ and the collars d⁴ d⁴, between which is the loose member d⁵, by means of which the said sleeve can be moved lengthwise on the shaft 75 D while rotating therewith. Disposed preferably at right angles to the starting-shaft D is the shaft E, carrying the fly-wheel E' and the bevel friction-gear e, the latter corresponding to the bevel-gear d³ on the sleeve 80 85 d² of the starting-shaft. The shaft E is connected by means of a crank e' and connecting-rod e² to any ordinary or preferred form of gasoline or other form of gas engine F. The details of construction of such gasoline or gas engine are well understood, and as they form no part of my present invention it is unnecessary to illustrate and describe them beyond calling attention to the well-understood fact that such form of engine requires to be 90 started or "turned over" to get the necessary compression and spark for igniting the compressed charge in the cylinder.

A pump G may be provided and operated from the shaft E through suitable connections, as the belt g', crank g², and connecting-rod g³, whereby said shaft E being properly turned the pump G will, through the pipe g, deliver water to the tank A, such water being supplied to the pump from a suitable source 100 through the pipe g⁴, as will be understood by those skilled in the art.

Suitably mounted adjacent the worm d' is the worm-wheel f, which, for identification and in view of its functions to be described, 105 may be denominated the "controller." The worm-wheel f has a cam f', secured to one face thereof, on which rides the roller f²

of a controlling-lever f^3 , pivoted at f^4 , a spring f^7 normally forcing the roller f^2 into engagement with said cam. Connected to the loose member d^5 on the sleeve d^2 is an arm f^4 of a bell-crank lever pivoted at f^5 , the other arm of such bell-crank being connected to the lever f^3 by means of a link f^6 .

From the construction described it will be clear that when the roller f^2 of the controlling-lever f^3 rides on the low part of the cam f' the spring f^7 will move the controlling-lever and its connections to cause the sleeve d^2 and gear d^3 to slide to the left and disengage the two gears d^3 and e and that when the roller f^2 rides on the high part of the cam f' the spring f^7 will be compressed and the sleeve d^2 moved to the right to carry the gear d^3 into operative engagement with gear e . As already described, the water-motor has the shaft D operatively connected thereto, so that when the water in the tank A falls sufficiently to lift the valve c from its seat the shaft D will be turned by the motor and through the worm d' the controller f will be operated and throw the gears d^3 and e into operative engagement. Thus through the shaft E , crank e' , and connecting-rod e^2 the gas-engine F will be given initial or starting movement.

It is to be noted that during the time that the water-motor W is operating to engage and disengage the gears d^3 and e and give initial movement to the gas-engine F the valve c is open and water is escaping from the tank A . It now becomes necessary to close the valve c and disengage the gears d^3 and e , so that the gas-engine through suitable pumping connections, as shown, may effectually replenish the water-supply in the tank, and when this has been accomplished it is also essential to stop the gas-engine, and consequently the pump, all as will now be explained.

Connected to the controller or worm-wheel f by a crank-pin h is a trip-actuating rod H , joined at its upper end to one arm h' of a bell-crank lever, the other arm h^2 of which is connected to a link h^3 , which is itself jointed to an arm h^4 , loosely mounted on the shaft b' and carrying a trip-cam h^5 , adapted to act upon the trip-arm b^5 of the trip-catch. The mechanism just described may consist of any usual form of dash-pot device and may be of any usual construction. Thus as the controller or worm-wheel f is turned the trip-actuating rod H is operated and through the parts described the trip-cam h^5 , acting on the trip-arm b^5 of the trip-catch, causes the hook b^4 of the trip-catch to be disengaged from the hook c^3 at the upper end of the valve-stem c^2 , as will be obvious, thus freeing the valve and permitting it to fall onto its seat and shut off the flow of water to the water-motor. The

disposition of the parts is such that this trip action takes place about the time the water-motor has caused the controller f to make one complete revolution, so that substantially at the same time that the water is cut off from the motor the controller-lever f^3 is actuated to disengage the gears d^3 and e , thus permitting the gas-engine F to continue in operation, as will be presently made more clear.

As has been generally hereinbefore referred to, the gas-engine, as usual, is to have its charge of compressed gas with air exploded at suitable times, all as usual in this class of devices, to give actuation to the moving part, and it is by virtue of this device, commonly termed the "sparking" device, that I have devised means for stopping the gas-engine, and consequently the pump, when the desired quantity of water has been supplied to the tank, such mechanism being as follows: Suitably secured to the top of the water-tank are the two similar contacts l , only one of such contacts being shown, since the other is a mere duplicate and of usual construction. To these contacts are connected the two wires l^1 l^2 of an electric circuit having a battery P . Pivotaly mounted upon the top of the water-tank at l^3 is the switch l^4 , adapted to connect the two contacts l , so as to complete the circuit. The end of the switch l^4 extends through a slot l^5 of an upright l^6 , the end of which rests upon the arm a' of the float. From this construction it will be seen that when the tank is full of water, as shown, the switch l^4 is raised from between the contacts l and the circuit l^1 l^2 is interrupted, so that the sparking device of the gas-engine is inoperative. When the water in the tank falls, however, the switch l^4 is permitted to drop and complete the circuit through the contacts l , whereupon the sparking device of the gas-engine is made operative to explode the gaseous mixture, as usual.

The operation of the device will be clear from the construction described and may be briefly stated as follows: When the water in the tanks falls to an undesirable level, the float a^2 of course falls with it, and through its connection with the arm b^2 and trip-catch the valve c is raised from its seat, so that water will flow to the water-motor W through the pipe c^4 , thus actuating the water-motor. The operation of the water-motor turns the shaft D and through the worm d' actuates the controller or worm-wheel f , which through the cam f' moves the controller-lever f^3 and throws into engagement the gear d^3 with gear e , whereupon the shaft E , and consequently the gas-engine connections joined thereto, will be given initial start of movement. At this time it will also be understood that the switch l^4 has completed the circuit of the

sparking device, so that the gas-engine being thus started will continue in operation, the water-motor in the meantime having turned the controller *f* through one revolution, causing a disengagement of the gears *d*³ and *e* and the closing of the valve *c* by means of the trip-cam and trip-actuating rod, as hereinbefore described. It is evident, of course, that the gas-engine being started in operation the pumping device will continue to supply water to the tank *A* until such time as the water therein has reached a desired height or level, whereupon the switch *b*⁴ is raised, as shown in the drawing, to break the circuit of the 15 sparking device, and thereby stop the gas-engine.

It has not been attempted herein to illustrate the details of the water-motor nor of the gas-engine, as such details form no part 20 of the present invention, and such devices, moreover, are well known to those skilled in the art and need no further description or illustration. It is obvious also that various 25 modifications may be made in the means by which the instrumentalities are operatively connected to maintain the water in the tank at the proper level and this without departing from the spirit of the present invention.

Having thus described my invention, what 30 I claim, and desire to secure by Letters Patent, is—

1. In a device of the character described, the combination of a water-tank, a valve in 35 said tank, a float, a trip-catch actuated by said float to raise the valve, a water-motor actuated by the water from the tank when the valve is raised, a gas-engine, a pump connected thereto, and means between the water-motor and gas-engine for starting the latter from the former.

2. In a device of the character described, the combination of a water-tank, a pump for 45 supplying water thereto, a gas-engine for operating said pump, a water-motor, means disposed between the water-motor and gas-engine for starting the latter from the former, and a float for automatically controlling the supply of water to the water-motor and the operativeness of the gas-engine.

3. In a device of the character described, the combination of a water-tank, a water-motor adapted to be actuated by water supplied 55 from said tank, a float in said tank, a valve, a trip-catch between the float and said valve for raising the latter as the water-level falls in the tank, a trip-cam, and means actuated by the water-motor for operating the trip-cam and releasing the valve.

4. In a device of the character described, 60 the combination of a water-tank, a pump for supplying water thereto, a gas-engine for operating said pump, a water-motor, devices for delivering water from the tank to the water-motor when the level of the water in the

tank falls, means disposed between the water-motor and gas-engine for starting the latter from the former and then freeing the gas-engine, and means for tripping said devices and shutting off the supply of water to the water-motor and thus stopping the same 70 after the gas-engine has been started.

5. In a device of the character described, the combination of a water-tank, a pump for supplying water thereto, a gas-engine for operating said pump, a water-motor, a valve 75 for controlling the supply of water from the tank to said motor, a trip-catch for operating said valve, a trip-cam, means operated from the water-motor for causing said trip-cam to trip the catch and free the valve, and 80 means between the water-motor and gas-engine for initially starting the latter from the former, and then freeing the gas-engine, and means for stopping the gas-engine when the water in the tank reaches a desired level. 85

6. In a device of the character described, the combination of a water-tank, a pump for supplying water thereto, a gas-engine for operating said pump, a water-motor, devices for delivering water from the tank to the water-motor when the level of the water in the tank falls, means disposed between the water-motor and gas-engine for starting the latter from the former and then freeing the gas-engine, and means for tripping said devices and shutting off the supply of water to the water-motor and thus stopping the same 90 after the gas-engine has been started, and means for automatically stopping the gas-engine when the water in the tank has 100 reached a desired level. 95

7. In a device of the character described, the combination of a tank, a float in said tank, a valve and connections between the float and valve for raising the latter when the level of the water in the tank falls, a water-motor operable by water delivered from the tank, a gas-engine, a pump operable thereby, 105 separable gear connections between the water-motor and gas-engine, a controller for operatively connecting and then disconnecting said gears, a trip-cam operable from the controller for tripping the connections between the float and valve to permit the latter to close connections between the tank and water-motor, and means for stopping the gas-engine when the water has reached a desired 110 level in the tank. 115

8. In a device of the character described, the combination of a tank, a float in said tank, a valve and connections between the float and valve for raising the latter when the level of water in the tank falls, a water-motor operable by water delivered from the tank, a gas-engine, a pump operable thereby, 120 separable operative connections between the water-motor and gas-engine, a controller operable from the water-motor for controlling 125

said connections for starting the gas-engine,
means for closing the valve in the tank after
the gas-engine has started to thereby stop the
water-motor, an electric circuit including the
5 gas-engine and means for making and break-
ing said circuit as the water falls and rises in
said tank.

In testimony whereof I affix my signature
in presence of two witnesses.
